UNITED STATES PATENT OFFICE.

HENRY C. ROOT, OF WESTGROVE, PENNSYLVANIA, ASSIGNOR TO THE ROOT DAIRY SUPPLY COMPANY, OF WESTGROVE, PENNSYLVANIA, A CORPORATION.

MILK-COOLER.

No. 884,860.

Specification of Letters Patent.

Patented April 14, 1908.

Application filed February 7, 1908. Serial No. 414,733.

To all whom it may concern:

Be it known that I, HENRY C. Root, a citizen of the United States, residing at Westgrove, in the county of Chester and State of Pennsylvania, have invented certain new and useful Improvements in Milk-Coolers, of which the following is a specification.

My said invention consists in certain improvements in the details of construction of 10 that class of liquid coolers designed particularly for cooling milk, which embodies a series of cylinders supported in a suitable rack or frame, and comprises means for supporting said cylinders so that each one may be 15 adjusted or removed and replaced without disturbing the position of the other cylinders, all as will be hereinafter more fully described and claimed.

Referring to the accompanying drawings 20 which are made a part hereof and on which similar reference characters indicate similar parts, Figure 1 is a side elevation of one of my improved milk coolers, Fig. 2 a view partly in end elevation and partly in vertical 25 section looking in the direction indicated by the arrows from the dotted line 2—2 in Fig. 1, Fig. 3 a detail sectional view on an enlarged scale of the construction shown at the upper right hand corner of Fig. 1 taken on the dotted line 4—4 in Fig. 2, and Fig. 4 a detail view of one of the end bars or racks.

In said drawings the portions marked A represent the frames or racks for supporting the cylinders, B said cylinders, and C C' the 35 water columns.

The racks A comprise bars or plates provided at suitable intervals apart with open sided rests or notches to receive the ends of the cylinders B. The openings into said rests 40 are of a size to readily receive the portion of the cylinder intended to rest therein, and permit it to be removed, adjusted, and replaced without disturbing the position of the adjacent cylinders. Their tops are each formed 45 with a recess with tapered sides into which may be set a trough-like receptacle A' for receiving the milk. Said receptacle A' has downwardly projecting flanges a cast to extend down on the outside of said racks A to 50 hold said receptacle in position. It is formed with a longitudinal ridge a⁶ in its center on each side of which a row of perforations a⁷ are formed in its bottom, as shown in Fig. 2. The lower ends of said racks A have flanges 55 a' on their outer faces which are adapted to

engage under inwardly projecting flanges a² on the ends of a receptacle A² which is thus suspended on said lower ends and adapted to receive the milk or other liquid after passing over the cylinders B. A discharge pipe a³ 60 leads from said receptacle A² to any point desired.

The cylinders B are each formed of corrugated sheet metal, as shown, and in each end have a cast metal hollow bushing b, which 65 is secured thereto by a water tight joint, preferably by soldering. Said bushings are adapted to rest in the notches or rests in the racks A and are each formed with a flange b'. Said flanges project a sufficient distance beyond the outside surface of the cylinders to prevent the milk from running over the ends of said cylinders. Said cylinders are arranged in the racks A, as best shown in Fig. 1, a sufficient distance apart to provide a 70 free air space between them, for a purpose to be presently described.

The water columns C C' are each of a similar structure except that one is provided with the inlet pipe c and the outlet pipe c', as 75 shown in Fig. 1. It will be understood, of course, that the arrangement might be reversed, and that with an odd number of cylinders in the stack the inlet pipe would be on one end of the machine and the outlet on the 80 other end. As shown in Fig. 1, both pipes are attached to the water column C on the right hand end of the machine but water column C' is provided with internally screw-threaded necks c² and c³ closed by screw-

threaded plugs c⁴, which enables said pipes c and c' to be transferred from one column to the other, as desired. Each column is formed with an opening for each cylinder in the stack, said opening being surrounded by 85 a flange c⁵ and containing a packing ring c⁶ of cork, or other compressible material, against which the tapered and rounded outer end of each bushing b may be forced into contact. The parts are all clamped and secured together by clamping rods 1, 2 and 3 formed 90 with screw-threaded ends and having wing-nuts 4, 5 and 6 respectively, thereon. Said rods extend through perforations in the racks A and through perforations in appropriate ears c' on the water columns C and C'. It will thus be seen that said columns may be drawn toward each other so that the outer 95 ends of the bushings b of the several cylinders B will be forced tightly into the outer 100 105 110

ends of the packing rings c^6 and tight joints thus secured. It will be noticed by reference to Figs. 3 and 4 that only the extreme ends of said bushings contact with said packing 5 rings, the contact being merely the pressure of the rounded end surface on each bushing into the compressible material of the packing ring. By means of this particular construction the loosening of the nuts upon the 10 clamping rods quickly releases the cylinders B from contact with the water columns sufficiently to permit them to be free to rotate in their bearings in the racks A or to be lifted out of said racks. The apparatus is prefer- 15 ably hung upon the outer end of the hook-shaped arm 8 forming a part of brackets attached to the wall of a building where the apparatus is to be used. Hooks 9 are cast on the top end of each water column adapted to 20 engage with said hooks 8 on said brackets. By loosening the clamping rods 1, 2 and 3, the cylinders B may be thoroughly washed and cleansed by being rotated in their bearings in the racks A without removing from 25 their positions and all parts of the apparatus thus made easily accessible for cleansing, enabling it to be conveniently kept in a sanitary condition. Nuts 10 and 11 are prefer- 30 ably provided on the screw-threaded portions of the clamping rods on each side of the racks A, whereby said racks may be rigidly supported in just the position desired and adjusted to hold the receptacles A' and A², or release them to enable them to be re- 35 moved, as desired. Should it be desired to remove one cylinder for the purpose of repair, or any other purpose, it can be readily done by reason of the open sided notches in the racks which enables any one to be lifted 40 out without disturbing the others.

As shown, the cold water passes in through 45 pipe c to water column C, then to the lower cylinder B and from thence through the water column C' into the next cylinder B and back into the water column C. A web e^9 is formed in each water column across the opening therein immediately beneath the passage from the cylinder B thereto, as indicated by dotted lines in Fig. 1, and as shown in section 50 in Fig. 4. By this means the water is prevented from accumulating in what would otherwise be pockets between the parts of the water columns which form portions of the through passage for the cooling agent, and thus causing injury by freezing or other causes.

The operation is as follows: The parts be-

ing assembled as shown in Fig. 1, the cooling agent, as cold water, brine, or any other such agent desired, is supplied from any suitable 60 source, enters through the pipe c and flows back and forth through the channel provided, leading through the cylinders B, and discharges through the pipe c'. The milk or other liquid to be cooled is placed in the receptacle A', is divided by the ridge a^6 and runs through the perforations in the bottom of said receptacle down on each side of the corrugated cylinders B, dropping from the surface of one cylinder to the surface of the 70 next until it reaches the receptacle A², from which it is conducted through the discharge pipe a^3 to a filling tank, or other receptacle as desired. The corrugated form of said cylinders not only increases the area of the 75 cooling surface but retards the flow of the liquid over it, thus increasing the efficiency of the apparatus in an important degree. The cylinders B being a distance apart, as shown in Fig. 1, the liquid in passing from 80 one to the other is freed from the heat by the action of the air, also, passing between said cylinders, which is a material aid in the operation of the apparatus.

The general construction and operation of 85 the device is similar to that shown in my application No. 339,470, filed Oct. 18, 1906.

Having thus fully described my said invention, what I claim as new and desire to secure by Letters Patent, is:

1. In a milk cooler, the combination, of the frame or racks containing open-sided bearings for the cylinders, the hollow cylinders mounted in said bearings, the water columns connected with the ends of said cylinders, means for feeding the milk to said cooler, means for supplying the cooling agent, and means for clamping the several parts of the structure together, substantially as set forth.

2. A milk cooler comprising water columns and rotatable cylinders with their ends engaging said columns, suitable supporting racks adjacent to said columns having open-sided rests in which the ends of said cylinders 105 are mounted, substantially as set forth.

In witness whereof, I, have hereunto set my hand and seal at Westgrove, Pa., this 31st day of January, A. D. nineteen hundred and eight.

HENRY C. ROOT. [L. S.]
